United States Patent

Des. 235,174
Patented May 27, 1975

235,174

HEM MARKER

Lee R. Gardner, Elmhurst, N.Y., assignor to Dyno Merchandise Corporation, Elmhurst, N.Y.

Filed Sept. 5, 1973, Ser. No. 394,594

Term of patent 14 years

Int. Cl. D6—99

U.S. Cl. D3—19

FIG. 1

FIG. 2

FIG. 3

FIG. 4

FIG. 5

FIG. 1 is a top plan view of a hem marker showing my new design;

FIG. 2 is an edge elevational view thereof;

FIG. 3 is a bottom plan view;

FIG. 4 is an end elevational view taken from the left end of FIG. 1; and

FIG. 5 is an elevational view of the opposite end.

I claim:

The ornamental design for a hem marker, as shown.
